CLAIM

The ornamental design for a tool rack, as shown and described.

DESCRIPTION

FIG. 1 is a front and top perspective view of a tool rack showing my new design;

FIG. 2 is a right side view of the tool rack in FIG. 1;

FIG. 3 is a left view of the tool rack in FIG. 1;

FIG. 4 is a right end view of the tool rack in FIG. 1;

FIG. 5 is a left end view of the tool rack in FIG. 1;

FIG. 6 is a top view of the tool rack in FIG. 1;

FIG. 7 is a bottom view of the tool rack in FIG. 1; and,

FIG. 8 is a front and top perspective view of the tool rack in FIG. 1 as in use.

The broken lines shown in FIG. 8 depict environmental subject matter, are for illustration only, and form no part of the claimed design.
